UNITED STATES PATENT OFFICE.

CHARLES H. FRIES, OF CHICAGO, ILLINOIS.

TOOL.

1,375,088.

Specification of Letters Patent. Patented Apr. 19, 1921.

Application filed July 29, 1918. Serial No. 247,148.

To all whom it may concern:

Be it known that I, CHARLES H. FRIES, a citizen of the United States, residing at Chicago, in the county of Cook and State of Illinois, have invented certain new and useful Improvements in Tools, of which the following is a specification.

This invention relates particularly to a tool for operating and cleaning pet-cocks.

10 An object of the invention is to provide a simple, compact tool which may be used as a wrench to grasp and turn the handle of a pet-cock to open and close the same, and which also may be used as a prod to clean 15 the opening in the cock.

Another object is to provide a combined wrench and prod in which each instrument acts as a handle to properly position and readily operate the other instrument.

20 The tool is especially adaptable for manipulating the drain cocks located in places not readily accessible, such, for example, as the cocks in the bottom of automobile radiators, especially those that are so placed in 25 Ford cars.

In the illustrated embodiment of the tool and its use,

Figure 1 shows the wrench end of the tool as applied to turn the valve of the pet-cock;

30 Fig. 2 shows the valve-cleaning end of the tool inserted in the registering passageways of the cock to remove any obstructions that may have become enmassed therein; and

Fig. 3 is a perspective view of the tool;

35 In all the views the same reference characters are employed to indicate similar parts.

5 represents a receptacle to be drained by the pet-cock 6. The tool 7 consists of a continuous rod, or wire of sufficient diameter, bent at right angles, as at 8, and returned upon itself, as at 9, to provide a hook which lies in a plane substantially at right angles to the plane of the body of the rod. This hook forms a wrench for engagement with the handle 10 of the pet-cock valve. When the tool is applied to the pet-cock valve, as shown in Fig. 1, rotation of the shank portion 7 serves to turn the valve in either direction, to open it or to close it.

50 The other end of the tool is bent, as at 11, to form a part 12 and a return portion 13,

which provide a pet-cock cleaning hook which lies in a plane substantially at right angles to the plane of the first hook. Portion 13 is tapered at its end, as at 14. The 55 part 13 is intended for insertion in the registering passage ways of the cock 6 when the valve 10 is open, as shown in Fig. 2, so as to clean out any dirt or accumulation that may be enmassed therein. Parts 12 and 13 60 serve as a handle when the device is used as a wrench, and parts 8 and 9 serve as a handle when the opposite end is employed for cleaning a pet-cock, as shown in Fig. 2. The length of the handle, or shank portion 7, 65 enables a person to reach a pet-cock that may be inconveniently and otherwise inaccessibly located.

The tool is very handy and convenient and adapted for opening and closing the valve 70 of a pet-cock and cleaning the same, by simply reversing the ends of the tool. The parts 12 and 13 being in a plane substantially at right angles to the opening between the parts 8 and 9, the operator can tell, by 75 the position of the part 13, the position of the handle 10 of the valve, so that he is enabled to ascertain thereby whether or not the valve is opened or closed. When the cleaning or prodding end of the tool is in 80 use the position or direction of the cleaning end thereof is indicated by the position of the wrench end. Thus each end of the tool acts as a handle to properly position and facilitate the operation of the instrument on 85 the other end thereof.

Having described my invention, what I claim is:—

A tool comprising a rod having one end bent into a hook for fitting over the handle 90 of a pet-cock to turn the same and lying in a plane substantially at right angles to the plane of the body of the rod, and having its other end bent into a pet-cock cleaning hook which lies in the plane of the body of the 95 rod at which the plane of the first hook is at right angles, said hooks acting alternately as handles for properly positioning and readily operating the hook at the other end.

In testimony whereof I hereunto subscribe my name.

CHARLES H. FRIES.
